(57) CLAIM

We claim the ornamental design for an embroidered towel with bow and hanger string, as shown and described.

DESCRIPTION

FIG. 1 is a perspective view of the claimed design.

FIG. 2 is a left-side elevation view thereof.

FIG. 3 is a right-side elevation view thereof.

FIG. 4 is a back elevation view thereof.

FIG. 5 is a front elevation view thereof.

FIG. 6 is a top plan view thereof; and,

FIG. 7 is a bottom plan view thereof.

The broken lines of an ornament and embroidered trees shown in the drawings are for illustrative purposes only and form no part of the claimed design.
